US00D465454S

(12) **United States Design Patent** (10) Patent No.: **US D465,454 S**
Kim (45) Date of Patent: **** Nov. 12, 2002**

(54) **TERMINAL FOR STORAGE BATTERY**

(75) Inventor: **Hwan-Chang Kim**, 38/5 495-11
Wueolpi-dong, Ansan-shi, Kyunggi-do,
428-855 (KR)

(73) Assignee: **Hwan-Chang Kim (KR)**

(**) Term: **14 Years**

(21) Appl. No.: **29/139,035**

(22) Filed: **Mar. 23, 2001**

(30) **Foreign Application Priority Data**

Jan. 5, 2001 (KR) 01-259

(51) LOC (7) Cl. **13-03**

(52) U.S. Cl. **D13/120**

(58) Field of Search D13/120; 439/762,
439/763, 764, 907

(57) **CLAIM**

The ornamental design for the terminal for storage battery, as shown.

DESCRIPTION

FIG. 1 is a perspective view;

FIG. 2 is a front view;

FIG. 3 is a rear view;

FIG. 4 is a left side view;

FIG. 5 is a right side view;

FIG. 6 is a top view;

FIG. 7 is a bottom view; and,

FIG. 8 is an exploded view.

1 Claim, 8 Drawing Sheets

FIG. 1

FIG. 2

FIG. 3

FIG. 4

FIG. 5

FIG. 6

FIG. 7

FIG. 8
